His ATTORNEY.

UNITED STATES PATENT OFFICE.

CALVIN B. PATCH, OF GLENELLYN, ILLINOIS, ASSIGNOR TO WILLIAM H. MINER, OF CHAZY, NEW YORK.

DRAW-BAR AND YOKE CONNECTION.

1,286,753.

Specification of Letters Patent.

Patented Dec. 3, 1918.

Application filed December 6, 1916. Serial No. 135,302.

To all whom it may concern:

Be it known that I, CALVIN B. PATCH, a citizen of the United States, residing at Glenellyn, in the county of DuPage and State of Illinois, have invented a certain new and useful Improvement in Draw-Bar and Yoke Connections, of which the following is a full, clear, concise, and exact description, reference being had to the accompanying drawings, forming a part of this specification.

This invention relates to improvements in draw bar and yoke connections.

One object of the invention is to provide a simple and efficient detachable draw bar and yoke connection wherein the draw bar may be removed without disturbing the yoke or parts contained therein.

Another object of the invention is to provide a detachable draw bar and yoke connection so arranged that old yoke straps of the riveted type may be employed with slight modification.

In the drawing forming a part of this specification, Figure 1 is a part longitudinal section, part side elevation of a draw bar and yoke illustrating my improvements in connection therewith. Fig. 2 is a transverse, vertical sectional view taken substantially on the line 2-2 of Fig. 1. And Fig. 3 is a horizontal sectional view taken substantially on the line 3-3 of Fig. 2.

In said drawing, A designates a draw bar, B a yoke and C a hollow head or hood. The yoke B is of a well known form and comprises upper arm 10, lower arm 11 and rear connecting portion 12 with a filler 13 secured thereto. The yoke is shown as formed of flexible material and will usually be made of wrought iron thereby adapting the arms to be sprung toward and from each other. As shown, each of the arms 10 and 11 is provided at its forward or free end with an elongated slot 14 to accommodate a correspondingly shaped lug 15 formed on the inner faces of the upper and lower horizontal walls 16 and 17 of the head C. The latter is of substantially rectangular form and in addition to the top and bottom walls 16 and 17 is provided with integral side walls 18-18 forwardly extended and having key slots 19 therein to accommodate the coupler key 20 by which the head is connected to the draw bar A.

The yoke strap B and head C are connected together by springing the arms 10 and 11 toward each other and snapping the same over the lugs 15-15. When thus assembled, it is apparent that the draw bar may be inserted within the head and when in position will prevent accidental disengagement of the arms 10 and 11 from the lugs 15. It is also apparent that the draw bar may be removed from the head by merely taking out the key 20 and without disturbing the yoke itself or any parts contained therein.

The slots 14 in the yoke arms and the lugs 15 are, or may be so designed that the ends of the slots 14 correspond to the usual standardly spaced rivet holes provided in yoke straps of the riveted type, and hence straps of said type may be employed with my invention by merely cutting out the intervening portion of the strap found between said rivet holes. In this manner, a material saving to the railroads can be effected since it permits the reemployment of the old riveted type of yoke straps while at the same time providing a detachable draw bar and yoke connection, substantially the only additional expense to the railroads being for the rectangular cast head.

I claim:

A yoke for railway draft riggings comprising a hollow rectangular head and an independent separable U-shaped yoke strap; means for detachably connecting the head and strap, said means comprising longitudinally extending slots in the arms of the yoke, the location of the ends of said slots corresponding to the usual standardly spaced rivet holes, and correspondingly shaped integral lugs on the inner faces of the upper and lower walls of the head, said lugs corresponding in depth to the thickness of the metal comprising the yoke strap, said head being adapted for detachable connection to a draw bar by means independent of said means for detachably connecting the head and strap.

In witness that I claim the foregoing I have hereunto subscribed my name this 4th day of December, 1916.

CALVIN B. PATCH.
